SEYMOUR W. BONSALL, OF NEWARK, NEW JERSEY, ASSIGNOR, BY MESNE ASSIGNMENTS, TO EUGENE W. SMALL AND ABRAHAM BENEDICT, TRUSTEES, OF NEW YORK, N. Y.

NATURAL AIR DRIER

Application filed June 28, 1928. Serial No. 289,004.

My present invention has relation to an improvement in rotary driers adapted to remove the moisture from various materials by the uniform action of air at a reduced atmospheric pressure and at a temperature generally lower than that of the atmosphere surrounding the drying machine.

It is one of the advantages of my improved drier that it can be utilized for evaporating liquids or semi-liquids and that the liquid to be evaporated can be fed into or supplied to my apparatus while the same is in operation, thereby saving the time necessary to recharge the apparatus from time to time.

It is a further advantage of the preferred form of my invention which is herein shown and described, that it may be readily adjusted with respect to the width of the air passages through which the drying current of air is forced, thereby regulating the degree of vacuum and the lowering of temperature produced with a given initial velocity of the drying air.

A preferred form of my invention is shown in the accompanying drawings wherein Fig. 1 is a view partly in section and partly in elevation of a complete apparatus equipped to evaporate liquids; Fig. 2 is a horizontal sectional view of the same taken directly over one of the trays, Fig. 3 is an enlarged detail partly in vertical section, showing the adjustable means for separating the trays and Figure 4 is an enlarged section through the upper bearing for the rotatable casing and the trays or support.

It is to be understood that, although I have shown in the drawings a special form of drier particularly adapted to the evaporation of liquids, the invention may be employed for the drying or dehydration of all kinds of materials and especially foods.

Essentially my improved apparatus comprises a central support or receptacle for the material to be acted upon whether liquids or solids, in combination with air scooping means arranged to rotate independently on the central support while maintaining such a relation to said support as to cause a current of drying air to pass through the same. The support is preferably held in a stationary po-

sition during operation of the machine, although this is not absolutely essential, so that the current of air passing through the drier rotates with the casing relatively to the support or receptacles.

In the specific form or embodiment of my invention herein shown the central portion which is destined to carry the material to be dried, dehydrated or evaporated comprises a framework having a top plate 10 and a bottom plate 11 united at intervals at the periphery by vertical braces 12. Within this frame may be inserted an appropriate number of trays, preferably circular shown at 13 which are placed horizontally over each other and are spaced apart preferably by means hereinafter described. These trays are shown with solid bottoms so as to hold liquids, but this is not essential to the broad invention.

Enclosing the receptacles 13 is a casing comprising a casing top plate 14 and a floor or casing bottom plate 15 united by vertical walls 16 and 17 placed symmetrically as shown in Figure 2. Carried by and preferably formed integral with the bottom, top and side walls of the casing are air scoops shown generally at 18 and 19 in Figure 2. In the preferred integral construction, the side walls of the casing are curved in opposite directions as indicated so as to form the scoops for the air at the entrance surfaces or openings 18 and 19. When the casing and scoops are rotated as will be hereinafter described in the direction indicated by the arrows in Figure 2, air will be gathered or taken in by the scoops or by the curved ends of the walls 16 and 17 and forced in separate streams across the receptacles.

The revolving air scoops carried by the outer casing 16 and 17 illustrate one form of means by which an air current may be set up through the casing. Where the rotation of the outer casing is at a relatively high speed, the air current set up by the scoops furnishes or directs sufficient air over the drying material to rapidly dry the same. The scoops also provide an extremely simple construction of means for setting up the air current and hence is the preferred construction.

The diametrically placed vertical walls 20

and 21 extend from a circular line close to the periphery of the central holding frame and circular trays outward to a point preferably about half way to the extreme edges of 5 the curved scoops; and the top and bottom plates 14 and 15 curve inward at the exit end of the passages on each side to meet the outer edges of the partitions 20 and 21, as shown at 22 and 23. The vertical walls 20 and 10 21 serve to dissipate the stream of air at the outlet ends of the passages thus formed to cause the discharged air to spread and spill over the curved edges of the top and bottom plates 14 and 15, and to be forced 15 out of the path of the intake openings.

The revolving part of the drier just described is supported upon a plate 24 having a hub 25 fixed to an upright shaft 26 preferably supplied with a bevelled gear 27 adapted 20 to be driven by a similar gear 28 on the end of a driving shaft 29. This shaft may be driven by any desired means as by the pulley 30.

Arranged concentrically with the upright 25 shaft 26, and on the upper side of the floor 15 is a ball-bearing 31 upon which rests the central bearing 32 of the central support, and preferably a stationary frame which supports the trays 13.

30 At the top of this frame and in alignment with the shaft 26 is fixed a stub shaft which extends upward through the top plate or cover 14. In the specific form shown, this stub shaft is hollow as shown at 33 and it 35 carries a flange 34 which confines an upper ball-bearing, revolving on the central plate 35 attached on top of the plate 14.

The hollow stub shaft 33 is fixed, as by a nut 36, to a pipe 37 extending down through 40 said shaft from a tank 38 carried by a fixed support 39. Between the tank 38 and the end of the shaft 33 is placed a valve 40 which may be opened and closed by means of a shaft 41 which can be turned by hand wheel 42 or 45 otherwise.

The tube 37 extends downward and turns at right angles just beneath the top of the stationary central frame where it is bent outward so as to extend vertically along the 50 periphery of said frame as shown at 43, where it is provided, at points between the trays 13 with short exit pipes 44 through which liquid may be allowed gradually to flow from the tank 38 into the various trays 13 either during 55 operation of the machine or otherwise.

To provide a means through which the trays 13 may readily be removed and replaced in the central support, the wall 16 of the revolving air scooping means is provided 60 with an opening 45. This opening is closed by a door 46, which is connected at one side to wall 16, by a hinge 47 and its other side may be provided with any suitable locking means 48 for securing the door in its closed position. 65 The revolving part of the drier is also pro-

vided, adjacent the top and bottom plates 14 and 15, with baffle plates 49 and 50. These baffles are located in each side of the air inlet passages and directly in front of the central support to prevent currents of air passing through the spaces above the top plate 10 and below the bottom plate 11 and to direct the full current of air through the spaces between the trays. 70

A means for readily adjusting the space 75 between the trays 13 is clearly shown in Figure 3. This means comprises a plurality of adjustable supports 51 located within each of the trays to support the trays one above the other in horizontally spaced relation. 80

The supports are each formed of a base 52 to rest upon the bottom of a tray and the base is provided with a central perforation threaded to receive the stem of an upwardly projecting headed screw 53 for supporting the 85 tray above.

By reason of this adjustable feature it is 90 obvious that the space between the trays 13 may be readily adjusted with respect to the width of the air passages through which the drying current of air is forced.

In operation the revoluble scoops create and cause an insistant and continuous force or current of air to pass in opposite directions through the spaces afforded between the trays. 95 The currents of air though passing in opposite directions do not oppose each other since each current has its own passage or path which preferably is on opposite sides of the casing 16, 17 or on opposite sides of the trays 13. The consequent reduction in air pressure over the produce in trays acts as a continuous partial vacuum, causing natural release of moisture, also lowering temperature. 100

It will be noted that by the construction 105 described herein, a receptacle 13 is provided to receive material either liquid or solid to be dried. Means are then provided to create or set up a current of air which is directed over the receptacle to dry the material therein. The means creating the current of air are carried upon a rotating carrier and therefore a rotating current of drying air is passing over the receptacles. 110

In the preferred construction the means for 115 creating the current of air is mounted or carried upon a rotating carrier. The rotating carrier in the embodiment shown herein is a casing 16, 17 surrounding the receptacle or receptacles and having at least one passage therethrough for directing at least one current of air over the receptacles and the material therein. With a casing rotating at a relatively high speed, the means or devices 120 for creating a current of air takes preferably the form of scoops carried by the rotating casing. These scoops are similar in function, operation and construction to the blades of a fan but adapted to the particular apparatus shown and described herein. 125 130

Various changes may be made in my apparatus without departing from the scope of my invention, and I do not limit myself to the details herein shown and described.

What I claim is:

1. A device for extracting moisture from matter comprising a plurality of removable receptacles disposed in stacked relation, a stationary support for said receptacles, and a rotary casing enclosing said stacked receptacles and provided with passages forming oppositely directed air channels through said casing adapted when the casing is rotated to direct air in opposite directions through the casing between said stacked receptacles. 70
2. A device for extracting moisture from matter comprising a plurality of removable receptacles disposed in stacked relation, a stationary support for said receptacles, a rotary casing enclosing said stacked receptacles and provided with passages forming oppositely directed air channels through said casing adapted when the casing is rotated to direct air in opposite directions through the casing between said stacked receptacles, said trays being spaced apart substantially a distance equivalent to the height of the tray. 75
3. A device for extracting moisture from matter comprising a plurality of removable receptacles disposed in stacked relation, a stationary support for said receptacles, a rotary casing enclosing said stacked receptacles and provided with passages forming oppositely directed air channels through said casing adapted when the casing is rotated to direct air in opposite directions through the casing between said stacked receptacles, and a door to give access to the receptacles in said casing. 80
4. A device for extracting moisture from matter comprising a plurality of removable receptacles disposed in stacked relation, a stationary support for said receptacles, a rotary casing enclosing said stacked receptacles and provided with passages forming oppositely directed air channels through said casing adapted when the casing is rotated to direct air in opposite directions through the casing between said stacked receptacles, and means for injecting matter into the trays during rotation of the casing. 85
5. In a device of the class described, a plurality of stationary trays disposed in stacked relation, a rotary casing enclosing said trays and having passages for the inlet and outlet of air, a hollow supporting shaft about which said casing rotates, a source of supply connected with the upper end of said hollow shaft and a discharge pipe connected with the lower edge of said hollow shaft and provided with a discharge orifice projecting into each of said trays to permit filling the trays when the casing is rotating. 90
6. A natural air drier comprising a receptacle for matter to be dried, means for sup-
- porting said receptacle in a stationary position, a rotary casing enclosing said receptacle and provided with oppositely directed passages adapted when rotated to direct air annularly through the casing over the receptacle. 95
7. A device of the class described comprising stationary supporting means, a removable tray carried by said supporting means, a rotatably mounted casing enclosing said supporting means, said casing being substantially rectangular and provided with an opening at each end, a radially disposed partition member near each end of the rotatable casing dividing the casing into parallel channels, means to produce a current of air in opposite directions in each channel across the removable tray, and means to rotate the casing. 100
8. A natural air drier comprising a rotary casing having inlet and discharge passages for air whereby when the casing is rotated air will pass through said casing, and a plurality of spaced trays supported in stationary stacked relation centrally of said casing whereby air drawn into said casing will be caused to pass between said trays through constricted passages and at accelerated velocity. 105
9. A natural air drier comprising a stationary support for matter to be dried, and a rotary casing enclosing said support, means in said casing forming a pair of parallel channels curved at opposite sides and ends forming deflectors when revolved for directing currents of air in opposite directions through the channels and over the stationary support, the deflecting end of each channel extending beyond the discharge end of the parallel channel, and means for rotating said casing. 110
10. A natural air desiccator for removing moisture from matter comprising a stationary support, a casing mounted to rotate about said support, and means in said casing for oppositely directing currents of air over the support, said casing being curved at its ends and provided with a substantially straight hollow body, and having an opening for the insertion and removal of matter to be dried. 115
11. A device of the class described comprising stationary supporting means, a removable tray carried by said supporting means, a casing rotatably mounted about said supporting means, radially disposed partition members carried by said casing dividing the casing into channels, means to create a current of air through the channels in opposite directions and across the removable tray, and means to rotate the casing. 120
12. A natural air drier comprising at least one receptacle for matter to be dried, means for supporting said receptacle, a rotary casing enclosing said receptacle, and means carried by said rotating casing for directing at least one current of air over the receptacle, 125

said current of air rotating relatively to the receptacle.

13. A natural air drier comprising at least one receptacle for matter to be dried, means for supporting said receptacle in a stationary position, a rotary casing enclosing said receptacle, and means carried by said rotating casing for directing at least one current of air over the receptacle, said current of air rotating relatively to the stationary receptacle.

14. A natural air drier comprising at least one receptacle means for matter to be dried, supports for the receptacle means, a casing means enclosing said receptacle and mounted independently thereof, devices carried by the casing means for creating at least one current of air which is directed by the casing means over the receptacles, and mechanism for rotating one of said means so that the current of air rotates relatively to the receptacle.

In testimony whereof I have hereto affixed my signature on this 27th day of June 1928.

SEYMOUR W. BONSALL.
